Attorney.

UNITED STATES PATENT OFFICE.

HENRY HAIGH, OF BATLEY, ENGLAND.

STOP MOTION OF LOOMS FOR WEAVING.

1,425,252.

Specification of Letters Patent. Patented Aug. 8, 1922.

Application filed August 1, 1921. Serial No. 489,022.

To all whom it may concern:

Be it known that I, HENRY HAIGH, a subject of King George V of Great Britain, residing at Batley, in the county of York, 5 England, have invented a new and useful Improvement Connected with Stop Motions of Looms for Weaving (for which I have filed an application in Great Britain on Feb. 1, 1917, Patent No. 110,267), of 10 which the following is a specification.

This invention has reference to looms for weaving in which fast and loose pulleys are employed and particularly to means for applying a brake to the fast pulley which has 15 been previously effected by a brake strap acting on a brake pulley, secured to the fast pulley and controlled by lever actuated by an inclined surface on a sliding rod connected to the knocking off lever, or operated 20 by incline on the strap fork bar, or by a brake block applied by spring or lever action. My invention has for its object the provision of improved means for self-actuatingly applying a brake to the fast or driving 25 pulley when the stop motion operates or the weaver actuates the knocking-off lever, so that the loom may be stopped when the shuttles are fully home in their boxes, whereby 30 "banging off" or violent concussion or vibration is prevented and breakage of the parts minimized.

In order that my invention may be fully understood reference is hereinafter had to the accompanying drawing, in which:—

35 Fig. 1 is an elevation, viewed from the rear of the loom, showing the application of my improved brake device to act on the fast pulley on stoppage of the loom;

40 Fig. 2 is an elevation of the parts looking in the direction of arrow A Fig. 1; and

Fig. 3 is a plan view of the brake device.

Referring to the drawing, I pivotally connect to a suitable stand *a* bolted to the floor or to a bracket secured to the part *b* of the 45 loom frame, a segmental plate or block *c* faced at *c'* with leather or the like and adapted when placed in operative position to engage with the periphery of the fast or driving pulley *d*, the said plate occupying a 50 position intermediate of the portions of the driving belt or strap *e* passing to and from the said pulley, and quite clear of same. The free end of the segmental plate has secured to or formed thereon an arm or extension *f*

to the outer end of which is secured a finger 55 or projection *g* extending outwardly at right angles to the said arm *f* and having on its underside at the outer end thereof an inclined cam or wedge shaped surface *g'* which is adapted to rest on and ride over a portion 60 of the strap guide *h*. The said strap guide is moved endwise in one direction to transfer the strap from the fast pulley *d* to the loose pulley *d'* by the operation of the weft stop motion, or by the weaver in stopping the 65 loom by hand, in the ordinary manner, and as the said strap guide *h* is thus moved rearwardly it wipes under the inclined surface *g'* of the finger or projection *g* and thus permits it to descend, the descent being assisted 70 by the retraction of a light spring *i* connected at one end to a link *k* attached by a plate *l* to the finger *g* and secured at the opposite end to the floor or any suitable fixed part. 75

The descent of the finger or projection *g*, causes the segmental plate, moving on its pivot connection, to be lowered into engagement with the periphery of the fast pulley and thus apply brake pressure thereto to 80 prevent violent concussion or vibration, and, on weft breakage, secure stoppage of the loom when the shuttles are fully home in the shuttle boxes, thus preventing traps or "banging off" and breakage of the parts. 85

On the re-starting of the loom, the strap guide *h* as it moves in the opposite direction to transfer the strap from the loose to the fast pulley, acts against the inclined surface *g'* of the finger or projection *g* and elevates 90 same to the position shown in Figs. 1 and 2, thus placing and maintaining the segmental plate or brake block *c* clear of the fast pulley during the normal running of the loom.

With my improvements the loom can be 95 turned by hand to any extent desired after the brake has been applied.

The parts of the mechanism are suitably constructed to admit of same being applied to suit the positions of the fast and loose 100 pulleys and the path of the driving strap, the stand *a* being adapted to be secured in the vertical position shown or in an angular position to adjust the segmental plate *c* in a convenient position over the driving pulley 105 to clear the driving strap, the other parts being adjustable also to accommodate them to the slight differences in position or con-

struction of the parts of the loom to which the improvements are applied.

Having thus described my invention, what I claim as new and desire to secure by Letters Patent is:—

1. The combination, with a fast pulley, a loose pulley, and a belt guide for moving a driving belt from one pulley to the other; of a stationary support, a friction brake block pivoted to the said support and adapted to bear on the fast pulley, and a finger secured to the brake block and provided with an inclined under surface which bears on the said belt guide and supports the brake block
- 10

clear of the fast pulley until the belt guide 15 has moved the driving belt from the fast pulley to the loose pulley.

2. In combination with the mechanism set forth in claim 1, means for pressing the said brake block forcibly towards the said fast 20 pulley.

In testimony whereof I affix my signature in the presence of two witnesses.

HENRY HAIGH.

Witnesses:

FRANK LURIE,
JAMES F. BEST.
